United States Patent Office.

WILLIAM PARKIN, OF TAUNTON, MASSACHUSETTS, ASSIGNOR TO REED & BARTON, OF SAME PLACE.

Design No. 4,697, dated March 7, 1871.

DESIGN FOR A TABLE-CASTER.

The Schedule referred to in these Letters Patent and making part of the same.

To all persons to whom these presents may come:

Be it known that I, WILLIAM PARKIN, of Taunton, of the county of Bristol and State of Massachusetts, have invented or produced a new Design for a Table-Caster; and do hereby declare the same to be described as follows and represented in the accompanying drawing, of which—

Figure 1 denotes a top view;

Figure 2, a front elevation; and

Figure 3, a side view of a table-caster containing such design.

The design has reference to the general form of the table-caster, as well as to its handle and corner column or post.

The corner posts, by which the base *a* and the cruet-sustaining rings *b b b* are supported, as represented at *c c c*—a four-bottle caster requiring four, and a three-bottle caster three of them; the base-plate *a* in one case being rectangular, and in the other triangular, in form. The form of each post is as represented.

The rings *b* are united by a plate, *g*, which serves also to support the handle, which is erected on such plate, there being at the centers of the plates *a* and *g*, and between such plates, a tapering column, *h*, having a bell-shaped base, as shown.

The handle is composed of two arched standards *A B*, one arranged within the other. The inner of the said standards terminates in curved feet *d d*, and is crowned by a bird, *e*, having partially-spread wings. The outer standard is surmounted by a barred knob, *f*.

The design for the caster embraces those of the posts, the base-plate, the rings, and the handle, and the center post, the design for the handle including the bird and the barred knob.

I claim—

1. The design for a caster, as set forth and shown.
2. The design for the handle, as shown.

WILLIAM PARKIN.
